(57) **CLAIM**

The ornamental design for a dehumidifier, as shown and described.

DESCRIPTION

FIG. 1 is a front elevational view of a dehumidifier showing our new design;

FIG. 2 is a rear elevational view of the dehumidifier shown in FIG. 1;

FIG. 3 is a left-side elevational view of the dehumidifier shown in FIG. 1;

FIG. 4 is a right-side elevational view of the dehumidifier shown in FIG. 1;

FIG. 5 is a top plan view of the dehumidifier shown in FIG. 1;

FIG. 6 is a bottom plan view of the dehumidifier shown in FIG. 1;

FIG. 7 is a left-front perspective view of the dehumidifier shown in FIG. 1;

FIG. 8 is a right-rear perspective view of the dehumidifier shown in FIG. 1; and,

FIG. 9 is a right-rear perspective view of the dehumidifier shown in FIG. 1 in a retracted configuration.

(Continued)

The broken lines shown in the drawings are for the purpose of illustrating portions of the dehumidifier that form no part of the claimed design.
